UNITED STATES PATENT OFFICE.

CYRILL KRALIČEK, OF CHICAGO, ILLINOIS.

AUTOMATIC ORGAN.

1,350,818.

Specification of Letters Patent. Patented Aug. 24, 1920.

Application filed October 22, 1919. Serial No. 332,417.

To all whom it may concern:

Be it known that I, CYRILL KRALIČEK, a citizen of Czechoslovakia, residing at Chicago, county of Cook, and State of Illinois,

5 have invented certain new and useful Improvements in Automatic Organs, of which the following is a specification.

This invention has as its object to provide an orchestrion gramophone, the same 10 being comprised of a plurality of cylindrical records upon which are recorded independently the sounds from different musical instruments, such as are used in an orchestra, all of the several records being timed and 15 operated to produce collectively the result of a complete orchestra, each of the records having its independent sound box and tone arm by which the volume and timbre of the music is directed outwardly.

20 A further object is to provide an instrument in which string musical instruments of the violin, viola, and contrabass types are actuated in connection with those of the wood-wind type as the flute, oboe, bassoon 25 and clarinet, and further combined with brass instruments, as the horn, trumpet and trombone, together with the percussive instruments as cymbals, triangle, tympani, and drum type, each sounding in accordance with 30 proper orchestra effects in a novel manner.

A still further object is to provide an instrument in which groups or series of records may be placed so that any of the groups may be brought into registration with the sound 35 reproducing means and then operated automatically as may be required.

These and other like objects are attained by the novel construction and combination of parts hereinafter described and shown in 40 the accompanying drawings, forming a material part of this disclosure, and in which—

Figure 1 is a front elevational view showing an instrument made in accordance with the invention.

45 Fig. 2 is a side elevational view of the same.

Fig. 3 is a vertical sectional view taken in another plane and indicating the application of electric power.

50 Fig. 4 is an enlarged fragmentary rear sectional view.

Fig. 5 is a partial vertical sectional view showing the front of the instrument, the cover plate being removed and,

Fig. 6 is a still further enlarged fragmental side elevational view of the sound box, parts being broken away in order to show the construction. 55

Referring to the drawings in detail, the numeral 10 indicates an upright rectangular casing, resembling in form part of an organ and provided with an extension 11 at the front ornamented in any desired manner, the open top being surrounded by an ornamental molding 12, as usual in casings 60 of this type of construction.

Revolubly mounted in the lower base portion of the casing is a shaft 15 having attached to one of its extending ends a crank handle 16, the same being provided with the 70 detents 17 adapted to engage any of the openings 18 formed centrally in disks 19 at the end of the casing.

Mounted within the casing, on the shaft 15 are a pair of spider-like heads 20 formed 75 with disks 21 arranged in equally spaced relation around the heads and centered in the disks are spindles 22 having secured upon them gears 23 by which they may each be independently actuated. 80

These gears are moved individually into mesh with a gear 24 fixed upon a spindle 25 which also carries a driving pulley 26, over which is trained a belt 27, driven by a pulley 28 fixed upon the motor shaft 29 of the motor 30, the same resting upon the bottom of the casing and adapted to be operated by lead wires 31 and 32 from a battery 33, or other source of electrical power, when the push button 34 is depressed encircling the 85 motor with the battery. 90

A gear 36 is also in mesh with the gear 24 so as to be actuated by it when the motor is operating, the gear 36 communicating motion to a worm 37 journaled in bearings 95 38 extending inward from the walls of the casing, the length of the worm being relative to the length of the individual record cylinders 40, engaged upon the spindles 22 which are rotated by the gears 23. 100

Engageable with the worm 37 is a toothed block 42 carried on the extreme upper end of a rod 43 passing upward through the coiled compression spring 44 fixed in the casing 45, the rod 43 having an angularly 105 turned, outwardly extending arm 46 passing through a slot 47 at the side of the casing and provided with an actuating knob

48 by which the block 42 may be removed from engagement with the worm and moved longitudinally so as to reengage with either end thereof when desired. The casing 45 5 rests upon the support 49 and pivotally secured to the casing 45 is a lever 53 in such manner as the knob is pulled in one direction as to convey a corresponding but opposite movement of the bar 50.

10 Pins 51 set in the bar 50 are operatively engaged in the lower, smaller downturned end of a plurality of curved conical tone arms 55 arranged in the upper portion of the casing. Having their open upper ends 15 arranged in a horizontal plane and extended rotatably through a plurality of openings 56 at the upper portion of the casing, the arms being of different diameter and magnitude according to the instrument represented by 20 the record, the sound of which is communicated outwardly.

The extreme lower ends of the sound arms 55, below the pins 51, are provided with curved seats 57 against which the rear upturned ends 58 of the sound box arms 59 make contact, the same being engaged by hollow plugs 60 entering the arms 55 and held therein by lugs through which pass pivot pins 62.

25 The front end of the sound arms 59 have secured in them diaphragms 63, in contact with which are the needles 64 their projecting ends being adapted to engage with the grooves of the record cylinders as best 30 shown in Fig. 3.

The levers rest upon the upper surface of the cylinders by gravity alone and obviously, as the records are rotated, the sound 35 reproduced by the contact of the needles 40 with the diaphragms is conveyed outwardly through the horns 55, the needles and heads being moved by the operation of the worm 45, in unison with the rotation of the records.

50 In operation, each of the several records 40 has inscribed upon it the sound produced by a musical instrument, such as one of the instruments used in an orchestra, the same being so timed and aligned with successive records, that when played as to produce an unbroken whole, giving a timbre and volume of sound not possible to attain by records 55 into which has been played a complete orchestra.

55 The playing is under control of the push button 35 which causes the motor to be energized and rotation of the worm gear in moving the several sound boxes and also for rotating the series of records at that time 60 disposed in an uppermost position so that the sounds recorded upon them are given forth.

In order to change from one series or 65 groups to another the extending knob 48 is depressed, disengaging the block 42 from

the worm, the block being then drawn outwardly so as to engage with the end of the worm; the detent 17 is then retracted, permitting the crank 16 to be rotated so as to bring another of the series of records into 70 playing position, whereupon they become locked by engaging the detents with any of the several openings 18, thus allowing any of the records to be replayed as desired.

75 From the foregoing it will be seen that a novel device for playing a plurality of independent but harmonically related or orchestrionated records has been disclosed whereby effects of an unusual nature may be attained.

Having thus described my invention what 80 I claim as new and desire to secure by Letters Patent, is—

1. In an orchestrion gramophone, the combination with a casing, a plurality of horns pivotally engaged in said casing, said horns 85 opening outward, sound boxes pivotally engaged at the lower ends of said horns, a cylindrical record on which each of said sound boxes is adapted to rest, each of said records carrying the sound from a separate instrument of music, means for rotating said records and means for actuating said sound boxes coincidentally therewith.

2. In an orchestrion gramophone, the combination with an upright casing, a plurality of horns pivotally engaged at their outer ends in said casing and opening outward therefrom, sound boxes pivotally engaged at the lower ends of each of said horns, a shaft mounted longitudinally in the 100 base of said casing, a pair of heads actuated by said shaft, spindles rotatable in said heads, a plurality of records disposed on said spindle side by side, each of said records being inscribed by a single instrument distinct from another and adapted when assembled to produce the tone volume and sound of the combined instruments, and means for rotating said shaft whereby any 105 of the several series of records may be brought into engagement with said sound boxes.

3. In an orchestrion gramophone, the combination with an upright hollow casing, a shaft centered therein, heads carried by 115 said shaft, spindles arranged in spaced parallel relation in said heads, a plurality of records engageable on said spindles in series representing a complete piece of music, each of said records presenting the sound from a 120 single musical instrument, means for rotating said shaft whereby any of said series may be brought into operation, a motor in said casing, means for actuating said motor, a worm driven by said motor, a threaded 125 head engageable with said worm, means for driving each of said spindles from said motor, a plurality of curved horns rotatably engaged at their outer ends in said casing, adapted to deliver volume of sound out- 130

ward, connections between said horns and said worm whereby they are moved in unison with the record, tone arms pivotally engaged at the lower ends of said horn, and
5 sound boxes combined with said tone arms, said sound boxes being adapted to rest by gravity upon the surface of said records,

whereby the sound of each musical instrument is combined and delivered outwardly from said casing. 10

In testimony whereof I have affixed my signature.

CYRILL KRALIČEK.
